PARAFFIN HYDROCARBON ISOMERIZATION

Ernest Solomon, Nutley, N. J., assignor to The M. W. Kellogg Company, Jersey City, N. J., a corporation of Delaware

Application January 29, 1942, Serial No. 428,646

4 Claims. (Cl. 260—683.5)

1

The present invention relates to the conversion of light normal paraffin hydrocarbons into branched chain hydrocarbons in the presence of a metallic halide catalyst, and one of its objects is the provision of an improved method of conducting metallic halide-catalyzed isomerization reactions. Although the invention is particularly advantageous in connection with the isomerization of normal butane, it may also be applied to the conversion of normal pentane and normal hexane; it is of utility in treating mixtures of these hydrocarbons, as well as in treating them individually.

The isomerizing ability possessed by certain metallic halides has engendered numerous proposals for using them to convert normal paraffins into iso-paraffins. The advantages thus sought to be obtained include not only the enhancement of the octane number and direct motor fuel value of the paraffins themselves, but also the development of sufficient chemical reactivity by isomerization to permit the subsequent catalytic alkylation thereof with normally gaseous olefins, leading to the production of increased quantities of high octane fractions boiling in the motor fuel range.

As in substantially all other types of hydrocarbon conversions, it is preferable in a commercial isomerization process that the conversion take place continuously, in order that operating costs may be kept low. Continuous isomerization processes heretofore known and used have involved the passage of hydrocarbons, preferably in the vapor phase, through a reaction zone containing a solid or liquid body of catalytic material while at a suitable conversion temperature. The chief catalysts employed have been bromides or chlorides of such metals as aluminum and zirconium. The latter substances are characterized by a tendency to sublime or vaporize at temperatures within the isomerization range, and thus to pass out of an isomerization reactor along with vaporous conversion products. Numerous expedients have been adopted to inhibit this tendency; for example, in a great many prior known isomerization processes, the metallic halide catalyst is either diluted with inactive halides of low volatility such as sodium chloride, or absorbed on a material such as silica gel or activated charcoal, or caused to react with a hydrocarbon to produce a complex, all with the end in view of stabilizing the catalyst by lowering its effective vapor pressure.

2

The rate at which hydrocarbons are converted by a metallic halide isomerization catalyst is profoundly influenced by the intimacy with which they are contacted with the catalyst. On this account prior known methods have involved either vigorous agitation in the liquid phase or, in treating vaporized hydrocarbons, the use of extended surface films of catalyst deposited upon porous supports. Owing to the tendency of the halide catalysts to become coated with heavy products of side-reactions, however, the maintenance of a large area of active catalyst surface has been a perplexing problem. It is possible to avoid the above difficulties, however, by employing a process wherein substantially the entire course of the isomerization reaction takes place in a homogeneous vapor phase, containing both the hydrocarbons to be converted and the catalyst. This method of operation provides an intimacy of contact which is far beyond anything attainable with solid or liquid catalysts, and affords other advantages.

The homogeneous vapor phase method of conducting catalytic isomerization necessarily involves two more or less conjugated procedures, viz.: (1) the vaporization and admixture of the hydrocarbons and the catalyst, and (2) the condensation and separation of the thus-formed mixture into its component parts, after the isomerization reaction has proceeded to the desired extent. The invention hereinafter described and claimed has for its principal object the provision of a unitary method of conducting the latter two conjugated steps in an efficient and substantially continuous manner.

The solid isomerization catalysts used in practicing the invention are, as previously pointed out, capable of passing directly from the solid to the vapor phase, and vice versa. When a homogeneous vapor phase mixture thereof with hydrocarbon vapors is cooled to effect condensation, the tendency of the catalyst substances is to deposit as solids on the cooling surfaces and thus gradually to reduce the heat transfer rate thereof and the access of the vapor mixture thereto. This situation may be remedied by special arrangements of apparatus or by periodically discontinuing operation of the condenser and removing accumulated catalyst deposits. It is contemplated by the present invention, however, to omit any and all provisions for preventing catalyst deposition or for removing accumulated catalyst from cooling surfaces. Instead, the deposits are al-

lowed to build up to a moderate extent, insufficient to interfere seriously with the functioning of the condenser, and then the flow of reactant vapors is reversed so that the accumulated catalyst deposit is stripped off by and admixed with fresh hydrocarbon feed vapors. By employing a pair of identical catalyst vaporizer-condenser units, situated at opposite ends of the isomerizing zone, the invention contemplates periodic flow reversal whereby each unit serves as a catalyst condenser during part of the operating time, and as a catalyst vaporizer during the remainder. Temperature conditions are so regulated that no hydrocarbons are condensed during condensation of the catalyst, that function being accomplished by a separate and subsequent condenser.

The catalysts which I use in practicing my invention are the volatile metallic halides heretofore found to possess isomerizing activity in the solid or liquid phase. I especially prefer to use aluminum chloride, however, because its activity is high in proportion to its cost and because it is not so active as to cause excessive side reactions at the somewhat elevated temperatures required to maintain it in the vapor phase. It is now known that the metallic halides depend for their isomerization activity upon the presence of certain promoting substances, in the absence of which they are substantially inactive. The promoters thus far found to be effective have for the most part been normally gaseous halogen compounds or compounds which are productive of gaseous halogen compounds under isomerization conditions. Thus, hydrogen halides have been used to a great extent; also, water will exercise a promoting effect on aluminum chloride because the two react to form hydrogen chloride. Other promoting substances known to be effective include certain alkyl halides, hydrogen bromide, and boron fluoride. It is contemplated by my invention to employ such a volatile promoting substance in connection with the catalysts of hydrocarbon isomerization by a vaporized metallic halide.

A general method of flow for an exemplary embodiment of my invention will now be described with reference to the accompanying diagrammatic flow sheet, wherein items of equipment are conventionally shown and from which most of the self-evident necessities such as pumps, valves and the like have been omitted for greater clarity. It is to be understood that the particular arrangement of apparatus shown and the particular process described are illustrative only and in no way limit the scope of the invention.

In the drawing, a stream of hydrocarbon material to be subjected to isomerization is taken from any suitable source and introduced into line 1 for transfer to a feed vaporizer or preheater 2, which may, for example, consist essentially of an externally heated pipe coil. If the feed is initially available as a liquid it is first vaporized in the coil 2 and then further heated, or if initially in vapor form is preheated directly. Preheated hydrocarbon vapors issuing from coil 2 traverse line 3 and enter a multiport valve 4. This valve is conventionally shown and suitably consists of a plug-type valve provided with four fluid connections spaced 90° apart around the body of the valve. The rotatable valve plug is bored with two independent passages, each of which describes a right angle so as to be capable of connecting two adjacent fluid connections. 75

The operative rotational range of the plug is 90°, and at one extreme thereof each of the four fluid connections leads via one of the plug passages to one of the two adjacent fluid connections lying on either side. At the other extreme each fluid connection leads via a plug passage to the other of the two adjacent fluid connections lying on either side.

Valve 4 as shown in the drawing is positioned initially so that line 3 leads through one of the plug passages into line 4. The alternate position of valve 4 is diagrammed as indicated by 4a and as will be subsequently described, provides for connecting line 3 with line 30, and line 5 with line 31. As positioned initially, lines 30 and 31 are connected through the other plug passage of valve 4.

Continuing through line 5, the preheated hydrocarbon vapors enter the shell of a catalyst vaporizer-condenser 6 which initially is serving as a catalyst vaporizer. Vessel 6 consists of a tube bundle 9 arranged as in a water tube-condenser, and having connections for the passage of water or other fluid through the tubes via inlet 7 and outlet 8. The hydrocarbon vapors entering the shell from line 6 contact the outside of tubes 9 and are withdrawn into line 11.

Prior to the commencement of the present operation, as will be hereinafter described, the outside of the tubes 9 will have been coated with a deposit of a volatile metallic halide isomerization catalyst. In passing through the shell of the vaporizer 6, the preheated hydrocarbon vapors become saturated with vaporized catalyst at the existing temperature. Inasmuch as the temperature of the hydrocarbon vapors is capable of being regulated by adjustment of the heat supplied to coil 2, the proportion of metallic halide in the saturated vapors may likewise be precisely controlled.

During its service as a catalyst vaporizer, the vessel 6 need not be supplied with cooling water via connection 7, and if desired steam or other heating medium may be passed through the tubes 45 9 to assist in vaporizing the catalyst. I prefer, however, to supply a small amount of cooling water sufficient to maintain the tube walls just below the sublimation temperature of the catalyst. In this way, it is possible to minimize the 50 flaking off of catalyst from the tubes and the accumulation of catalyst in the bottom end of the shell. The same object is furthered by employing tubes having artificially roughened outer surfaces. If desired the tubes 9 may be finned 55 or baffled in such a way as to prevent catalyst from falling to the bottom of the shell.

The mixed hydrocarbon and catalyst vapors withdrawn from vessel 6 into line 11 enter a multiport valve 12 which, as is clearly shown by the drawing, has three fluid connections spaced 90° apart and a plug with a T-shaped passage, whereby the fluid connection to which line 11 is joined may lead via a right angle turn into line 13 or in a straight line (as is indicated by the diagram 12a) into line 40. In the initial operation the valve is positioned so as to divert the mixture of hydrocarbon and catalyst vapors into line 13, whence they pass to another multiport valve 14, the mode of operation of which will be clear 65 from the already given descriptions of valves 4 and 12. Via valve 14 the reactant mixture passes into line 15 and is joined by a gaseous stream of a suitable promoter substance, such as dry hydrogen chloride gas, introduced through line 16. 70 The complete mixture next enters a heat ex-

changer 17 wherein it is heated to the desired reaction temperature. It continues through line 18 into an empty reactor vessel 19, the interior of which constitutes the isomerization reaction zone. The vessel 19 is made of such a volumetric capacity as will provide a sufficient time of transit of the reactant gas mixture therethrough, during which the isomerization of the hydrocarbons proceeds to the desired extent. Upon issuing from the reaction zone the reactant gas mixture travels through line 21 to a multiport valve 2 which, as is indicated in the drawing, serves to divert the stream into line 23 in this initial operation. An alternate position of valve 22 is shown in the adjacent diagram 22a.

From line 23 the reactant gas mixture traverses multiport valve 24 into line 25 and thence enters a second catalyst vaporizer-condenser 26, which in this initial operation is serving as a catalyst condenser. The construction of 26 is identical in all respects with that of vessel 6 already described, and comprises tubes 29 which are supplied with water via inlet 27 and outlet 28.

As the reactant gas mixture enters the shell of the catalyst condenser 26, water is being passed through the tubes at a temperature and rate sufficient to cool the mixture to a point just slightly above the dew point of the hydrocarbons therein. At such a temperature substantially all or at least a major portion of the catalyst condenses as a solid on the exterior of the tubes 29, while the hydrocarbons and promoter substance remain uncondensed. The latter materials, together with minor amounts of the catalytic metallic halide vapors, are withdrawn from the shell of condenser 29 into line 30, and after traversing multiport valve 4 as indicated, they pass through line 31 into a product condenser 32. Water is passed through the shell of the tubular condenser 32 via inlet 33 and outlet 34; the entering gas mixture is introduced into the tubes, wherein by indirect heat exchange the temperature is lowered and all constituents are condensed except the normally gaseous promoter substance. The latter material should, in practicing this embodiment of the invention, have a substantially higher volatility than either the hydrocarbons or the metallic halide catalyst.

In condenser 32 the flow of the condensing vapors is upwardly through the externally cooled tubes 28 which are preferably of relatively large diameter. Hydrocarbons which condense in the upper portions of the tubes flow downwardly along the inside walls thereof, so that the minor amounts of metallic halide catalyst also condensed are prevented from depositing directly on the tube walls and obstructing the passing of the rising vapors. A suspension of solidified metallic halide in liquid hydrocarbon material is carried down into the bottom of condenser 20 and drawn off to line 35. Gaseous promoter material remains uncondensed, and is removed from the upper end of condenser 20 into line 16 for re-admixture with additional quantities of reactants, as previously described.

The liquefied hydrocarbons withdrawn into line 35 are passed to a settling drum 36 wherein the small amounts of solidified metallic halide catalyst are separated by gravity. They are removed as a slurry by drawing them off from the bottom of the settler 36 into line 37, whence they may be transferred to a recovery step suitably involving vaporization of the accompanying hydrocarbon material by heating or pressure reduction. Any suitable method may be used for

recovering the traces of catalyst carried over, so that it may be re-used in the process.

The clear supernatant hydrocarbon liquid is withdrawn from settler 36 through line 38, and as it constitutes the gross conversion product of the process it may be disposed of as desired. In the case of butane isomerization it will ordinarily be preferable to separate the iso-butane made in the process from unconverted normal butane, the latter being then recycled for further conversion along with additional amounts of fresh feed. As will be hereinafter more specifically explained, a high percent conversion of normal to iso compounds in one pass through the reaction zone is not usually aimed at in this process. Conversion of 100 per cent of the charge in one pass cannot be accomplished in any event, because the isomerization reaction equilibrium constants do not permit.

After the process as thus far described has been continued for some time, the coating of catalyst originally present on the exterior of the tubes 9 in the vaporizer 6 will become depleted, while at the same time the exterior of the tubes 29 in the catalyst condenser 26 will become coated with catalyst to such an extent that their capacity for heat removal will be reduced. At an appropriate point, before either of the latter two occurrences have proceeded far enough to interfere with the operation of the process, the five multiport valves 4, 12, 14, 22 and 24 are simultaneously rotated into their alternate positions as shown in diagram 4a, 12a, 14a, 22a and 24a. At the same time the flow of cooling water to the condenser 26 is discontinued or at least greatly reduced while an abundant supply of cooling water is supplied to vaporizer 6. Thereupon vaporizer 6 becomes operative as a catalyst condenser, and condenser 26 becomes operative as a catalyst vaporizer. The newly established flow of hydrocarbons, catalyst and promoter substance is then as follows: From line 3 the preheated vapors pass into line 30, thence through the vaporizer 26 wherein they are saturated with catalyst, thence through line 25, valve 24, line 39 and valve 14 into line 15 wherein they are admixed with promoter substance, and thence through line 18 and heat exchanger 17 into reactor 19 as already described with reference to the initial operation.

The reactant materials leaving reactor 19 through line 21 go through valve 22 into line 40, thence through valve 12 into line 11, and the catalyst is condensed out in 6. Hydrocarbons and promoter material leave the condenser 6 through line 5 and after traversing valve 4 into line 31 they enter product condenser 20, after which they are handled in exactly the same manner as has already been described with reference to the initial operation.

It will be understood by hydrocarbon process engineers that numerous procedural steps in the above described embodiment of my invention may be replaced by alternate and equivalent steps. For example, I may accomplish the vaporization of a metallic halide catalyst by passing only a portion of the vaporized hydrocarbon charge through a catalyst vaporizer, reuniting this catalyst vapor-carrying portion with the main charge stream prior to its entry into the reaction zone. With the latter arrangement it is possible to dispense with the exchanger 17, and to vaporize and heat the charge directly to an isomerizing temperature in the feed vaporizer 2. The amount of catalyst vapor admixed with the charge is

then controlled by varying the proportion of the charge passed through the catalyst vaporizer, rather than the temperature thereof. Also, it may be desirable in some cases to work under a pressure high enough to dissolve a substantial amount of the promoting substance in the reaction products condensing in 32, and to separate the promoter for re-use in a subsequent fractional distillation of the hydrocarbon liquid withdrawn through line 38.

The operations thus far described have assumed the initial presence of a coating of catalyst on the exterior of the tubes 9 in condenser-vaporizer 6. Such a deposit may be formed prior to the commencement of hydrocarbon conversion by passing heated air through a body of catalyst in any suitable container and then leading the catalyst-saturated air through the vessel the tubes of which are to be coated, while passing cooling water through said tubes to condense out catalyst thereon. This operation is necessarily repeated during occasional shut-downs of the conversion operation, in order to return to the system those small amounts of catalyst which escape through line 37.

Referring now more specifically to the operating conditions which are usable and desirable in practicing the invention, it will be understood that the temperature of hydrocarbon vapors passed through a catalyst vaporizer such as 6 in the drawing is readily chosen in accordance with known principles of vaporization so that the hydrocarbon vapors will, when saturated therewith, contain a proper amount of the catalyst vapors. The requisite temperature at which to vaporize the catalyst is jointly determined by the per cent catalyst vapors desired in the reactant mixture, the temperature-vapor pressure characteristics of the chosen metallic halide catalyst, and the pressure. The first of the latter three variables is subject to considerable variation, depending upon the activity of the particular catalyst employed, the type of hydrocarbons to be treated, and the extent of conversion desired. It may range from as low as 1 mol per cent up to about 15 mol per cent of the weight of the hydrocarbon charge. The pressure in the catalyst vaporizer is preferably the same as that desired to be maintained in the conversion zone, of which more will be said. There must of course be a sufficient quantity of catalyst in the vaporizer vessel to enable a state of saturation to be attained by the hydrocarbon vapors while they are in contact therewith.

Referring now to the conditions in the conversion zone itself, it will be understood that the pressure and temperature are necessarily limited to those conditions which will maintain the hydrocarbon charge in the vapor phase. I prefer, furthermore, that in no case shall the temperature be lower than about 200° F. nor higher than about 700° F., for at lower temperatures only minute amounts of catalyst can exist as vapor in admixture with the hydrocarbons, and at higher temperatures side reactions supervene.

The conversion pressure, except as it is limited by the foregoing considerations, may be from atmospheric to about 2000 pounds per square inch. The higher pressures must in general be accompanied by higher temperatures in order to maintain both the charge and the catalyst in vapor phase. The choice of a temperature and pressure at which to carry out the isomerization reaction is, as previously indicated, limited by

the per cent catalyst vapors desired to be present, and vice versa, inasmuch as the per cent of catalyst vapor which can be maintained in a hydrocarbon vapor saturated therewith varies inversely with the system pressure and directly with the temperature. Thus, if aluminum chloride is taken as the catalyst and a concentration of 10 mol per cent thereof is to be maintained in the reaction zone, the temperature must be not lower than about 300° F. at atmospheric pressure, and not lower than about 350° F. at 100 pounds per square inch absolute, for otherwise the desired catalyst concentration will be above the saturation point of the hydrocarbon charge.

10 The reaction times and the promoter concentrations which are usable in practicing the invention are likewise amenable to considerable variation. The reaction time can be as short as one minute or as long as several hours, depending upon the type of hydrocarbon material treated and the extent of conversion desired. The longer reaction times are not very practicable in a commercial operation, however, because of the unduly large reaction vessel which they require. 15 The latter difficulty is made somewhat less acute by operating at the higher pressures. The promoter concentration in the reactant vapor mixture is preferably between about 1 and about 10 mol per cent of the hydrocarbon, about 5 per cent being preferred.

An important limitation exists as to the pressure and temperature conditions which may be permitted to exist in a catalyst condenser such as 26 in the initial operation previously described.

20 As already mentioned, the temperature in such a condenser must be kept above the dew point of the hydrocarbon vapors, in order to prevent condensation thereof. It must also be low enough to accomplish the condensation of a major portion and preferably substantially all of the catalyst. Both the latter requirements are influenced by the pressure, and the former is influenced by the volatility of the hydrocarbons treated. In order that there may be a temperature capable of 25 satisfying both the latter requirements, the pressure must be limited. Thus in the case of butane isomerization the pressure during catalyst condensation should be below 500 pounds and is preferably below 300 pounds, while for pentane, the corresponding pressures are 200 and 100 pounds respectively, assuming the use of aluminum chloride as a catalyst. A suitable pressure is readily calculable in any given case using published thermodynamic data. In the event that the requisite catalyst condensation pressure is 30 below the desired conversion pressure, expansion of the reacted vapor mixture prior to catalyst condensation will be necessary.

35 While I have described my invention with reference to certain embodiments thereof for illustrative purposes, my invention is limited only by the following claims.

I claim:

40 1. The method for isomerizing hydrocarbons which comprises passing hot hydrocarbon vapors through a catalyst vaporizing and condensing zone and into contact therein with a normally solid volatile metallic halide isomerizing catalyst deposited in solid form upon the heat transferring surfaces of means adapted for the indirect exchange of heat between different fluid streams to effect the formation of a vaporous mixture of hydrocarbon vapors and vapors of the normally solid metallic halide isomerizing catalyst, passing 45 the resulting vaporous mixture out of contact

with said solid metallic halide catalyst and into an isomerization reaction zone free from deposited solid metallic halide isomerizing catalyst and sufficiently large to provide a holding time effective to permit the reaction to proceed, maintaining said gaseous mixture in said reaction zone under isomerizing conditions which prevent any substantial condensation of said vaporized metallic halide catalyst in said reaction zone, then passing said reaction mixture through a second catalyst vaporizing and condensing zone in contact with heat transferring surfaces of means adapted for the indirect exchange of heat between different streams, maintaining said heat transferring surfaces in said second catalyst vaporizing and condensing zone sufficiently cool to effect substantial condensation and deposition of said normally solid metallic halide isomerizing catalyst without condensing hydrocarbons, then reversing the flow of the vaporized hydrocarbons whereby they flow first through said second catalyst vaporizing and condensing zone to vaporize metallic halide isomerizing catalyst previously condensed and deposited therein from the said vaporous mixture of hydrocarbon and metallic halide vapors, passing the last-mentioned vaporous mixture through the reaction zone in the manner described, and then passing the reaction mixture from the reaction zone through said first catalyst vaporizing and condensing zone under conditions effective to condense and deposit therein metallic halide isomerizing catalyst without condensing hydrocarbons.

2. A process in accordance with claim 1 wherein normal paraffin hydrocarbons of 4 to 6 carbon atoms to the molecule are isomerized.

3. The method for isomerizing hydrocarbons which comprises passing hot hydrocarbon vapors through a catalyst vaporizing and condensing zone and into contact therein with an aluminum chloride isomerizing catalyst deposited in solid form upon the heat transferring surfaces of means adapted for the indirect exchange of heat between different fluid streams to effect the formation of a vaporous mixture of hydrocarbon vapors and vapors of the aluminum chloride isomerizing catalyst, passing the resulting vaporous mixture out of contact with said solid aluminum chloride and into an isomerization reaction zone free from deposited solid aluminum chloride and sufficiently large to provide a holding time effective to permit the reaction to proceed, maintaining said gaseous mixture in said reaction zone under isomerizing conditions which prevent any substantial condensation of said vaporized aluminum chloride in said reaction zone, then passing said reaction mixture through a second catalyst vaporizing and condensing zone in contact with heat transferring surfaces of means adapted for the indirect exchange of heat between different streams, maintaining said heat transferring surfaces in said second catalyst vaporizing and condensing zone sufficiently cool to effect substantial condensation and deposition of said aluminum chloride isomerizing catalyst without condensing hydrocarbons, then reversing the flow of the vaporized hydrocarbons whereby they flow first through said second catalyst vaporizing and condensing zone to vaporize aluminum chloride isomerizing catalyst previously condensed and deposited therein from the said vaporous mixture

of hydrocarbon and aluminum chloride vapors, passing the last-mentioned vaporous mixture through the reaction zone in the manner described, and then passing the reaction mixture from the reaction zone through said first catalyst vaporizing and condensing zone under conditions effective to condense and deposit therein aluminum chloride isomerizing catalyst without condensing hydrocarbons.

- 10 4. The method for isomerizing hydrocarbons which comprises passing hot hydrocarbon vapors through a catalyst vaporizing and condensing zone and into contact therein with a normally solid volatile metallic halide isomerizing catalyst deposited in solid form upon the heat transferring surfaces of means adapted for the indirect exchange of heat between different fluid streams to effect the formation of a vaporous mixture of hydrocarbon vapors and vapors of the normally solid metallic halide isomerizing catalyst, passing the resulting vaporous mixture out of contact with said solid metallic halide catalyst and into an isomerization reaction zone of relatively large cross-sectional area and free from deposited solid metallic halide isomerizing catalyst and sufficiently large to provide a holding time effective to permit the reaction to proceed, maintaining said gaseous mixture in said reaction zone under isomerizing conditions which prevent any substantial condensation of said vaporized metallic halide catalyst in said reaction zone, then passing said reaction mixture through a second catalyst vaporizing and condensing zone in contact with heat transferring surfaces of means adapted for the indirect exchange of heat between different streams, maintaining said heat transferring surfaces in said second catalyst vaporizing and condensing zone sufficiently cool to effect substantial condensation and deposition of said normally solid metallic halide isomerizing catalyst without condensing hydrocarbons, then reversing the flow of the vaporized hydrocarbons whereby they flow first through said second catalyst vaporizing and condensing zone to vaporize metallic halide isomerizing catalyst previously condensed and deposited therein from the said vaporous mixture of hydrocarbon and metallic halide vapors, passing the last-mentioned vaporous mixture through the reaction zone in the manner described, and then passing the reaction mixture from the reaction zone through said first catalyst vaporizing and condensing zone under conditions effective to condense and deposit therein metallic halide isomerizing catalyst without condensing hydrocarbons.
